CHARLES S. GURR AND JAMES S. POPE, OF VIENNA, GEORGIA.

HOLDER FOR PLOW OR CULTIVATOR SCRAPES OR SWEEPS.

Application filed June 23, 1927. Serial No. 200,917.

This invention relates to holders for the scrapes or sweeps of plows and cultivators, and has for one of its objects to improve and simplify devices of this kind to the end that they may involve a one-piece construction. To attain this and other ends, the invention comprehends the provision of a device of this character which shall embody a slightly curved body or plate provided at its front side with upper and lower lugs adapted to engage in the plow or cultivator standard and provided at its rear side and upper end with a lug adapted to engage the upper edge of the scrape or sweep.

The invention is hereinafter more fully described and claimed, and illustrated in the accompanying drawing, wherein:

Figure 1 is a view partly in elevation and partly in vertical section illustrating the application of the scrape or sweep holder,

Figure 2 is a sectional view taken on the plane indicated by the line 2—2 of Figure 1,

Figure 3 is a detail perspective view of the scrape or sweep holder, and

Figure 4 is a similar view of the scrape or sweep holder looking at the same from another angle.

Referring in detail to the drawing, 1 designates the standard, 2 the point, 3 the scrape or sweep and 4 the heel bolt of a plow or cultivator.

The holder comprises a plate 5 which occupies a position between the standard 1 and the intermediate portion of the scrape or sweep 3 and which is slightly curved so as to fit snugly against the rear edges of the standard. The plate 5 is provided with a vertically arranged and closed end slot 6 for the reception of the heel bolt 4, and it is provided at its front side with upper and lower lugs 7 which enter the standard 1 and serve to hold the plate against turning movement on the heel bolt. The plate 5 is provided at its rear side with a lug 8 which contacts with the upper edge of the intermediate portion of the scrape or sweep 3 and serves to hold the

scrape or sweep against turning movement on the heel bolt 4. The lug 8 extends from the upper edge of the plate 5 to the upper end of the slot 6 and from one lateral edge of the plate to the other, and it is provided with a central recess 9 of arcuate formation.

As the scrape or sweep holder is of one-piece construction, it may be manufactured and sold at a comparatively low cost, it may be readily positioned on the heel bolt 4, and the scrape or sweep 3 may be readily applied to or removed from the heel bolt. When the scrape or sweep 3 is removed from the heel bolt 4, the holder functions as a washer for the nut 10 for the heel bolt. The scrape or sweep holder will positively hold the scrape or sweep 3 in its proper position on the standard 1 of the plow or cultivator, and its upper end is materially reenforced by the lug 8.

It should be understood that the drawing is merely illustrative and does not pretend to give exact proportions. Furthermore, the said drawing is illustrative of a preferred construction, it being our expectation that various changes and modifications may be made without departing from the spirit and scope of our invention.

What is claimed is:—

A scrape or sweep holder comprising a slightly curved plate provided with a vertical slot closed at its ends, lugs formed integrally with the plate at points above and below the slot and extending forwardly from the front side of the plate, and a lug formed integrally with the upper end portion of the plate and extending rearwardly beyond the rear side of the plate, said last named lug extending from the upper edge of the plate to the upper end of the slot and from one lateral edge of the plate to the other, the last named lug having a central recess.

In testimony whereof we affix our signatures.

CHARLES S. GURR.
JAMES S. POPE.
